(57) **CLAIM**

We claim the ornamental design for a notched pole clamp for medical device, as shown and described.

DESCRIPTION

FIG. 1 is a front right perspective view of a notched pole clamp for medical device.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is a rear left perspective view thereof.

Items shown in broken lines depict environment and portions of the notched pole clamp for medical device that form no part of the claimed invention. The dash-dot lines represent the bounds of the claimed design.
